(57) **CLAIM**

The ornamental design for a cradle for remote control for electric home appliances, as shown and described.

DESCRIPTION

FIG. 1 is a top front perspective view of a cradle for remote control for electric home appliances showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8. is a front elevational view of using state thereof.

The broken lines are for illustrative purposes only and form no part of the claimed design.
